UNITED STATES PATENT OFFICE.

JOSEPH HREN, OF KINGSTON, NEW YORK.

TAPE-CUTTING MECHANISM FOR BOOK-BACKING MACHINES.

1,261,538.

Specification of Letters Patent.

Patented Apr. 2, 1918.

Original application filed September 11, 1914, Serial No. 861,158. Divided and this application filed June 9, 1917. Serial No. 173,865.

To all whom it may concern:

Be it known that I, JOSEPH HREN, a citizen of the United States, residing at Kingston, in the county of Ulster and State of New York, have invented an Improvement in Tape-Cutting Mechanisms for Book-Backing Machines, of which the following is a specification.

This invention relates generally to devices for automatically cutting into substantially uniform lengths, in transit, a continuously advancing strip or strips, and the present application is a division of my earlier application, filed September 11, 1914, Serial No. 861,158.

The device of this invention is primarily designed to be an appurtenance to a book or pad backing machine, such as that shown and described in the parent application aforesaid. In such a machine, properly assembled piles of superposed sheets are successively fed into the machine, through which they are carried in processional order by suitable advancing mechanisms, a continuous strip of adhesive tape being fed into the machine and brought into proper contact with the edge of each pile of sheets to back the same in the usual manner, the tape being severed between the piles as the same are advanced and after application thereto. As this cutting operation should be automatic, and as it is practically impossible to feed the assembled piles of sheets into the machine with invariable regularity, it will be apparent that the cutting mechanism should be operated or released for operation by each pile of sheets in turn as it reaches a certain point in its path of movement. Furthermore, the cutting operation must be practically instantaneous, in view of the fact that the tape must be severed without interruption of advancing movement of the piles of sheets. Therefore, it has been found impracticable to provide a cutting mechanism which is actuated by each of the advancing piles, in turn, and necessary to provide a cutter which is normally operative but which is checked under yielding forces by each advancing pile while the latter is in the path of movement of the cutting blade.

The principal object of the present invention is the provision of cutting mechanism of the character set forth which shall be entirely automatic, comparatively simple

in construction, durable, not likely to get out of order, and efficient and dependable in operation.

My invention will be more readily understood by reference to the accompanying drawings, forming a part of this specification, in which

Fig. 1 is a side elevation of a device embodying my invention;

Fig. 2 is an end elevation thereof, partly in section;

Fig. 3 is an enlarged horizontal section, taken substantially on the line 3-3 of Fig. 2;

Fig. 4 is a vertical section, taken substantially on the line 4-4 of Fig. 3;

Fig. 5 is a vertical section, taken substantially on the line 5-5 of Fig. 3;

Fig. 6 is a detail view, in side elevation, with parts in section, of the mechanism shown in section in Fig. 3, and

Fig. 7 is a detail view showing the preferred manner of mounting the cutting blade.

Referring now to the drawings in detail, numeral 11 may be assumed to designate the bed or table of a book backing machine, along which piles 12 of sheets or blanks are advanced and guided by any suitable mechanism, preferably such as shown and described in detail in my co-pending application aforesaid. As also shown and described in said co-pending application, a continuous strip 15 of adhesive tape is applied to the edge of each pile 12 in transit, and the present invention has to do with mechanism for automatically severing the strip 15 between the piles 12 without interruption of advancing movement.

Journaled in suitable bearings supported upon the main frame or table of the machine and driven from any suitable source of power—preferably as shown and described in said earlier application—is the vertical shaft 16 carrying the beveled gear 17 in mesh with the beveled gear 18 on the shaft 19 which is journaled in bearings at the upper ends of arms 20 and 21 suitably mounted upon the frame of the machine. A sleeve 22 is revolvably mounted on the shaft 19, and at the end of this sleeve is mounted a circular hub or collar 23 which is provided with an end portion 24 of reduced diameter from which reduced portion projects diametrically the lug 25. Adjacent

to the hub 23, the shaft 19 is provided with an enlarged portion 19', for a purpose which will subsequently be made clear, and upon this enlarged portion 19' is revolvably mounted the sleeve 26 having an enlarged cup-shaped extremity 27 adapted to surround the reduced end of the hub 23, as best shown in Fig. 3. A diametrically disposed lug 28 projects inwardly from one side of the flange 10 which forms the cup-shaped extremity 27 of the sleeve 26, and secured to this lug is a round rod 29, which is curved to conform substantially to the degree of curvature of the periphery of the hub 23 but which is not 15 in contact therewith or with the interior walls of the cup-shaped portion 27 of the sleeve 26.

In the annular channel formed between the walls of the cup 27 and the hub 23, 20 is mounted the coil spring 30, in compression between the lugs 25 and 28, and into this coil projects the curved rod 29. This spring is designed to be in some compression when in condition of maximum expansion, with 25 the lugs 25 and 28 in contact, as shown in Fig. 5, and obviously will be further compressed when the parts 24 and 27 are so rotated with reference to each other as to separate said lugs.

30 Slidably secured in suitable openings near that end of the sleeve 26 which is opposite the cup-shaped portion thereof are the two similar plugs 31 and 32, preferably in diametrical alinement with respect to the enlarged portion 19' of the shaft 19, the inner ends of which are in-curved to conform to the curvature of the shaft, and between said inner ends and the enlarged portion 19' of said shaft are the removable friction wearing surfaces 33 and 34, of leather or similar material. Mounted on the sleeve 26 over the plugs 31 and 32 is the collar 35, through threaded openings in which is passed the set-screws 36 and 37, so located that the interior ends of said screws impinge against the ends of the plugs 31 and 32 in the manner shown in Fig. 4. The purpose of the plugs 31 and 32, with the wearing surfaces 33 and 34 and the set screws 36 and 37, is to 45 control the degree of frictional contact between the sleeve 26 and the shaft 19 by regulating the pressure of said wearing surfaces against said shaft. In this manner, the pressure may be so regulated that when 50 the shaft 19 is revolved, and the hub 23 checked against revolution therewith, the frictional contact will be sufficient to cause the sleeve 26 to revolve with the shaft 19, thereby separating the lugs 25 and 28 and 55 compressing the coil spring 30, until the free end of the arm 29 engages the lug 25, thereby checking further rotation of said sleeve 26, the shaft 19 continuing to revolve against the wearing surfaces 33 and 34 of the plugs 60 31 and 32. It will now be seen that under

these conditions energy has been stored in the spring 30, subjecting the hub 23 to yielding pressure tending to revolve the same.

Mounted on the hub 23 is the knife or cutter blade 38, preferably provided with a curved cutting edge 39. As this blade is to sever a moving strip by rotation about a fixed axis which parallels the strip, it is obvious that its connection with the hub 23 upon which it is mounted should not be inflexible, and I therefore secure this blade by means of screws 40 to a bracket 41, which is pivotally secured to the hub 23 by means of a pivot pin 42 passing through suitably apertured lugs on said hub and said bracket. 75 A coil spring 43 serves to yieldingly retain said blades rectangularly disposed with reference to the shaft 19, but capable of pivotal movement on the pin 42 away from the hub 23, to swing said blade to an inclined 80 position, or even to a position substantially parallel to the shaft 19. It will therefore be seen that after the cutting operation, should the next succeeding pile of sheets engage the blade 38 before sufficient time has 85 elapsed to permit withdrawal of said blade from the path of movement of said pile, said blade will merely be swung thereby to an inclined position, against the action of the spring 43, thus clearing the path of movement of said pile.

90 Suitably carried by the frame of the machine is a rod 44, adjustably secured to which is an arm 45 carrying a bracket 46, and journaled in a suitable bearing carried 100 by said bracket is a shaft 47 having mounted thereon, near one end thereof, a sprocket wheel 48. The shaft 47 is driven in any suitable manner from a moving element of the machine—preferably as shown and described in my co-pending application aforesaid. A shaft 49 is secured at the lower end of the bracket 46 and has revolvably mounted thereon a sprocket wheel 50 driven from the sprocket wheel 48 by means of the sprocket 110 chain 51. A circular feed roller or disk 52 is also revolvably mounted on the fixed shaft 49 and is connected with the sprocket wheel 50 in such manner that both are caused to 115 revolve upon revolution of the shaft 47.

A downwardly projecting bracket 53 is secured to the side of the frame of the machine, the center line of which is in approximately the same vertical plane as that of the axis of the disk or roller 52, and at its lower 120 end said bracket carries a shaft 54 revolvably mounted in the sleeve 55 which forms a part of said bracket. A short arm 56 is secured at one end of said shaft 54, said arm having a roller 57 mounted at the free end 125 thereof. At the other end of the shaft 54 is secured a vertical arm 58, which is held in a desired position by means of a coil spring 59 interposed between the bracket 53 and the arm 58. A vertical arm or plate 60 130

is secured to one end of a substantially horizontal arm 61, the other end of which is pivotally mounted to the frame of the machine. At its lower end, the arm or plate 60 rests upon the roller 57 carried by the arm 56, and at the upper end of the arm 61 is mounted a roller 62, said roller projecting through a slot 63 in the main table 11 whereby a part of the periphery of said roller 5 normally projects above the upper surface of said table directly underneath the disk 52. Pivotal movement of the arm 58, due to oscillation of the shaft 54, is limited by stops 64 and 65, said stops being so located that 10 when the roller 62, the arm 60, the shaft 54 and the arm 58 are in what may be termed their normal positions, the upper end of the arm 58 slightly clears a lug or stop 66 (Fig. 7) on the hub 23, while when the roller 62 15 has been so depressed that the extreme upper point of its periphery is on substantially the same level as the upper surface of the main table 11, thus slightly revolving the shaft 54 from its normal position by depression 20 of the roller 57 by the arm or plate 60, the upper end of the arm 58 will be in position to engage the lug or stop 66 on the hub 23 and thus prevent revolution of said hub around the shaft 19 in a direction to carry 25 the blade 38 in the direction of the table 11. The coil spring 59 tends to retain the arm 58 in such position that the roller 62 will extend slightly above the upper surface of the main table 11, and to return said roller to 30 said position when displaced therefrom.

It will now be apparent that the passage 35 of a pile of superposed sheets 12 over the surface of the table 11 and underneath the disk 52, will result in depression of the roller 62 substantially to the level of the table top, and will cause the arm 58 to be moved into a position such that its upper end will engage the lug or stop 66 on the hub 23 and thus prevent revolution of said hub, holding 40 the blade 38 substantially in a vertical position, as shown in Fig. 2. However, as soon as the pile 12 of sheets has passed out of contact with the roller 62, the reaction of the coil spring 59 will return the roller 62 to its 45 initial or normal position, and in such manner change the position of the upper end of the arm 58 to throw the same out of engagement with the lug or stop 66, thus permitting the reaction of the compressed coil 50 spring 30 to rapidly revolve the hub 23 and therewith the blade 38, which crosses the path of movement of the tape 15 and passes through a suitable slot (not shown) in the edge of the table 11, thereby severing the 55 tape close to the end of the edge of the pile 60 of sheets of blanks.

On completion of its partial revolution, due to the reaction of the spring 30, the hub 23 continues to revolve, due to the continuous revolution of the shaft 19, and if by the

time the blade 38 has returned to its substantially vertical initial or normal position another pile of sheets has not been interposed between the disk 52 and the roller 62, the hub with the blade mounted thereon will 70 continue to revolve at practically the same speed as the shaft 19, and will again sever the tape, if the latter is still interposed in the path of movement of said blade. In the normal operation of the machine, however, 75 the piles of sheets are so spaced apart as they are fed into the machine that by the time the blade 38 has returned to its initial or normal position, as aforesaid, the next succeeding pile of sheets will be in position 80 to depress the roller 62, thus bringing the upper end of the arm 58 into position to engage the lug or stop 66 and hold the hub 23 stationary until the pile of sheets has cleared the roller 62, again releasing the hub 23 for 85 a repetition of the severing operation.

Many modifications of minor details of my improved tape cutting mechanism for book backing machines and the like will doubtless readily suggest themselves to those 90 skilled in the art to which it appertains, and I therefore do not desire to limit my invention to the specific construction herein shown and described.

I claim as new and desire to secure by Letters Patent:

1. In a machine for advancing in continuous procession individual piles of assembled sheets having applied to an edge of each thereof a continuous strip of adhesive 100 tape, mechanism for severing the tape between said piles which comprises a spring-actuated, rotatable cutting blade operable in one direction only, and means rendered operative by the interposition of a pile of 105 assembled sheets therein and in the path of movement of said blade for checking said blade against rotation under action of its spring.

2. In a machine for advancing in continuous procession individual piles of assembled sheets having applied to an edge of each thereof a continuous strip of adhesive tape, mechanism for severing the tape between 110 said piles which comprises a spring-actuated, rotatable cutting blade operable in one direction only, normally inoperative means for checking said blade against rotation under action of its spring, and means for rendering said checking means operative when 115 a pile of sheets in transit is in the path of movement of said blade.

3. In a machine for advancing in continuous procession individual piles of assembled sheets having applied to an edge of each 120 thereof a continuous strip of adhesive tape, mechanism for severing the tape between said piles which comprises a spring-actuated, rotatable cutting blade, means for continuing rotation of said blade to initial op- 125

erative position after each cutting operation, and means actuated by each advancing pile of sheets in turn to check said blade in such position under action of its spring when a pile of sheets is in the path of movement thereof.

4. In a machine for advancing in continuous procession individual piles of assembled sheets having applied to an edge of each thereof a continuous strip of adhesive tape, mechanism for severing the tape between said piles which comprises a spring-actuated cutting blade, and means rendered operative by the interposition of a pile of assembled sheets therein and in the path of movement of said blade for checking said blade against movement under action of its spring, said blade being mounted for yielding lateral displacement in the direction of the advancing piles.

5. In a machine for advancing in continuous procession individual piles of assembled sheets having applied to an edge of each thereof a continuous strip of adhesive tape, mechanism for severing the tape between said piles which comprises a spring-actuated cutting blade, normally inoperative means for checking said blade against movement under action of its spring, and means for rendering said checking means operative when a pile of sheets in transit is in the path of movement of said blade, said blade being mounted for yielding lateral displacement in the direction of the advancing piles.

6. In a machine for advancing in continuous procession individual piles of assembled sheets having applied to an edge of each thereof a continuous strip of adhesive tape, mechanism for severing the tape between said piles which comprises a spring-actuated cutting blade, means for returning said blade to initial operative position after each cutting operation, and means actuated by each advancing pile of sheets in turn to check said blade in such position under action of its spring when a pile of sheets is in the path of movement thereof, said blade being mounted for yielding lateral displacement in the direction of the advancing piles.

7. In a machine for advancing in continuous procession individual piles of assembled sheets having applied to an edge of each thereof a continuous strip of adhesive tape, mechanism for severing the tape between said piles which comprises a rotary spring-actuated cutting blade, means rendered operative by the interposition of a pile of assembled sheets therein and in the path of movement of said blade for checking said blade against movement under action of its spring, and means for energizing said spring while said blade is held in its checked condition, said blade being mounted for yielding lateral displacement in the direction of the advancing piles.

8. In a machine for advancing in continuous procession individual piles of assembled sheets having applied to an edge of each thereof a continuous strip of adhesive tape, mechanism for severing the tape between said piles which comprises a driven shaft, a rotating element loose upon said shaft and carrying a cutting blade adapted upon revolution thereof to intersect the path of movement of said tape, a frictionally driven rotating element on said shaft, a spring interposed between said elements, and means rendered operative by the interposition of a pile of assembled sheets therein and in the path of movement of said blade for checking movement of said loose element and thereby storing energy in said spring under continued rotation of said frictionally driven element.

9. In a machine for advancing in continuous procession individual piles of assembled sheets having applied to an edge of each thereof a continuous strip of adhesive tape, mechanism for severing the tape between said piles which comprises a driven shaft, a rotating element loose upon said shaft and carrying a cutting blade adapted upon revolution thereof to intersect the path of movement of said tape, said blade being mounted for yielding lateral displacement in the direction of the advancing piles, a frictionally driven rotating element on said shaft, a spring interposed between said elements, and means rendered operative by the interposition of a pile of assembled sheets therein and in the path of movement of said blade for checking movement of said loose element and thereby storing energy in said spring under continued rotation of said frictionally driven element.

10. In a machine for advancing in continuous procession individual piles of assembled sheets having applied to an edge of each thereof a continuous strip of adhesive tape, mechanism for severing the tape between said piles which comprises a driven shaft, a rotating element loose upon said shaft and carrying a cutting blade adapted upon revolution thereof to intersect the path of movement of said tape, a frictionally driven rotating element on said shaft, a spring interposed between said elements, normally inoperative means, rendered operative by the interposition of a pile of assembled sheets therein and in the path of movement of said blade, for checking movement of said loose element and thereby storing energy in said spring under continued rotation of said frictionally driven element, and means for positively limiting the extent of relative rotation of said elements.

11. In a machine for advancing in continuous procession individual piles of assembled sheets having applied to an edge of each thereof a continuous strip of adhesive

tape, mechanism for severing the tape between said piles which comprises a driven shaft, a rotating element loose upon said shaft and carrying a cutting blade adapted 5 upon revolution thereof to intersect the path of movement of said tape, said blade being mounted for yielding lateral displacement in the direction of the advancing piles, a frictionally driven rotating element on said 10 shaft, a spring interposed between said elements, normally inoperative means, rendered operative by the interposition of a pile of assembled sheets therein and in the

path of movement of said blade, for check-ing movement of said loose element and 15 thereby storing energy in said spring un-der continued rotation of said frictionally driven element, and means for positively limiting the extent of relative rotation of said elements. 20

In testimony whereof I affix my signature in presence of two witnesses.

JOSEPH HREN.
